SHOULDER STRAP

Filed March 6, 1930

INVENTOR.

Agnes Winterbottom

BY

Solter & Plachek
ATTORNEY

UNITED STATES PATENT OFFICE

AGNES WINTERBOTTOM, OF NEW BEDFORD, MASSACHUSETTS

SHOULDER STRAP

Application filed March 6, 1930. Serial No. 433,538.

This invention relates to new and useful improvements in a shoulder strap.

The invention has for an object the provision of a device of the class mentioned which is of simple durable construction, dependable in use and efficient in action, and which can be manufactured and sold at a reasonable cost.

The invention proposes a short horizontal back strap portion for attachment along the back top edge of a chemise or other lady's garment and integral with a pair of shoulder strap portions for extending over one's shoulder, the free ends of the shoulder straps being for attachment to the front edge of said garment, the junctions of said back strap portion with said shoulder strap portion being folded and secured together so that the shoulder strap portions are directed at obtuse angles to said back strap portion, and a reinforcing strap attached on each shoulder strap portion at a point a short distance from the back strap portion and angularly directed towards the back top edge of the garment for attachment.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a perspective view of a chemise with the straps attached.

Fig. 2 is a developed view of the shoulder straps, per se.

Fig. 3 is an enlarged fragmentary detailed view of a portion of Fig. 2.

Fig. 4 is an enlarged fragmentary detailed view of a portion of Fig. 2.

Fig. 5 is a view similar to Fig. 4, but showing the strap partially open, before the application of stitches to hold the parts together.

Fig. 6 is a fragmentary view similar to Fig. 4, but illustrating a modified form of the device.

Fig. 7 is a perspective view of a portion of Fig. 6.

Fig. 8 is an enlarged detailed plan view of Fig. 7.

The shoulder straps consist of a short horizontal back strap portion 10 for attachment along the back top edge of a chemise or other lady's garment and integral with a pair of shoulder strap portions 11 for extending over one's shoulders, the free ends 12 of said shoulder straps being for attachment to the front edge of said garment, the junctions 13 of said back strap portion 10 with said shoulder strap portions 11 being folded and secured together so that the shoulder strap portions are directed at obtuse angles to the back strap portion 10, and a reinforcing strap 14 attached on each shoulder strap 11 at a point 15 a short distance from the back strap portion 10 and angularly directed towards the back top edge of the garment for attachment.

In Fig. 1, a chemise 16 has been illustrated in which the front is indicated by reference numeral 17 and the rear by numeral 18. This chemise has a back top edge 19 and a front top edge 20. The back strap portion 10 shown attached along the back top edge 19 and the reinforcing straps 14 are shown also attached to this edge. The free ends 12 of the shoulder strap portions are shown attached to the front top edge 20 of the chemise. Preferably the back strap portion 10 should be about two inches long. The various attaching is accomplished with stitches.

The folds at the junctions 13 consist of an angular bottom fold 21 connecting the back strap portion 10 with a small triangular filler portion 22 and an angular top fold 23 connecting the filler portion 22 and the shoulder strap portion 11. This is clearly shown in Fig. 5. Stitches 24 are arranged upon the junction to hold the parts together and conclude the formation. The reinforcing straps 14 are connected with the shoulder strap portions 11 by stitches 25. In Fig. 2 dot and dash lines 26 indicate a fragmentary portion of the chemise.

In the modified form of the device illustrated in Figs. 6, 7 and 8, an adjustable means has been illustrated for holding the folded condition of the junctions 13 between the back strap portion 10 and the shoulder strap

portions 11 so that the size of the obtuse angle, before referred to, may be varied. This means consists of a plate 27 attached upon the back strap portion 10 and formed with 5 an apex portion 28. The attaching of the plate 27 on the back strap is accomplished by stitches 29 engaged thru apertures 30 formed in the plate.

The apex portion 28 has a bottom inclined 10 side 31 adapted for engaging along the fold 21 and determining the shape and position of this fold. A block 32 is attached upon the front face of the plate 27 and has an arcuate side 33 and an aperture 34 extending from 15 this arcuate side completely thru the block. A second apex member 35 is slightly spaced from the apex member 28 and is formed with an arcuate side 36 engaging against the arcuate side 33 of the block. 20 The apex member 35 is provided with a stud 37 which extends thru the aperture 34. A nut 38 threadedly engages on the stud for holding the apex member 35 in various adjusted positions. Dot and dash lines 39 indicate 25 another position of the apex member. The apex member 35 is formed with a top edge 40 adapted to engage in the fold 23 shown in Fig. 5 for determining the angular position of this fold. It will be seen that in 30 adjusted positions of the apex member, the angular relation of the shoulder strap portion to the back strap portion will be adjusted. The filler portion 22 engages in the space between the apex members 28 and 35.

35 While I have shown and described the preferred embodiment of my invention, it is to be understood that I do not limit myself to the precise construction herein disclosed and the right is reserved to all changes and modifications coming within the scope of the invention as defined in the appended claims.

40 Having thus described my invention, what I claim as new, and desire to secure by United States Letters Patent is:—

45 1. A shoulder strap for a chemise or other lady's garment, comprising a short horizontal back strap portion for attachment along the back top edge of a chemise or other lady's 50 garment and integral with a pair of shoulder strap portions for extending over one's shoulder, the free ends of said shoulder strap portion being for attachment to the front edge of said garment, the junctions of said 55 back strap portion with said shoulder strap portions being folded and secured together so that the shoulder strap portions are directed at obtuse angles to said back strap portion, a reinforcing strap attached on each 60 shoulder strap portion at a point a short distance from the back strap portion and angularly directed towards the back top edge of the garment for attachment, and adjustable 65 means for holding the folded condition at the junctions of said back strap portion with the

shoulder strap portions so that the size of said obtuse angle may be varied,

2. A shoulder strap for a chemise or other lady's garment, comprising a short horizontal back strap portion for attachment along 70 the back top edge of a chemise or other lady's garment and integral with a pair of shoulder strap portions for extending over one's shoulder, the free ends of said shoulder strap portion being for attachment to the front 75 edge of said garment, the junctions of said back strap portion with said shoulder strap portions being folded and secured together so that the shoulder strap portions are directed at obtuse angles to said back strap portion, a reinforcing strap attached on each shoulder strap portion at a point a short distance from the back strap portion and angularly directed towards the back top edge of the garment for attachment, and adjustable 80 means for holding the folded condition at the junctions of said back strap portion with the shoulder strap portions so that the size of said obtuse angle may be varied, comprising a plate with an apex portion attached upon the 85 back strap portion and supporting a second apex member for engaging against and holding the folds.

In testimony whereof I have affixed my 90 signature.

AGNES WINTERBOTTOM.
